UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed March 5, 1926. Serial No. 92,491.

It is frequently desirable to feed paper to a typewriting machine either alone or associated with a carbon sheet, from a roll of paper, and in such cases it is also desirable that the roll shall have an endwise movement in unison with the carriage of the typewriting machine in order that the paper may be fed in a direct line to the platen at all times. If such a roll carrying attachment is supported on the carriage, it so increases the weight thereof as to render the carriage more or less sluggish in action and imposes added work upon the typist in removing the carriage to begin a new line.

An object of this invention is to construct a roll carrying attachment which may be adapted to carry one or a plurality of rolls of paper or similar material, which attachment shall be supported entirely by the main frame of the machine, and will run freely on trackways carried by said main frame so that none of the weight of the attachment is imposed on the travelling carriage of the typewriter. The invention embodies a simple and efficient attachment for this purpose which will be more particularly disclosed in the following detailed description and set forth in the appended claims.

In the drawings:

Figure 1 is a side elevation of a portion of a typewriting machine provided with the attachment constituting the subject matter of this invention with some parts in section.

Figure 2 is a fore and aft section of the platen and associated parts showing the paper severing knife.

Figure 3 is a front view of the roll carrying attachment detached from the machine.

Figure 4 is a top plan view of the same.

Figure 5 is a front elevation of one side member of the roll holding frame.

Figure 6 is a similar view of the other side member.

Figure 7 is a side view of the member shown in Figure 6.

Figure 8 is a perspective view of the spindle for the paper roll.

Figure 9 is a detailed view showing the operative connection between the typewriting machine carriage and the roll supporting frame.

From many points of view the invention is applicable to any of the usual commercial typewriters, but it is illustrated in connection with the standard Royal machine, for

which it is in some ways, particularly adapted. There is disclosed a portion of a main frame A in which is supported a shift frame B upon which travels the carriage C by means of interposed ball bearings D. The carriage supports the usual platen E which is shiftable, as indicated by dotted line position in Figures 1 and 2 and against the front side of which strike the usual type bars D. The platen is provided with front paper feed rolls G and rear paper feed rolls H, operated by the usual rock shaft I. The carriage also embodies the usual paper apron K. Side arms L are pivoted to the sides of the paper carriage at M and at their front ends are connected by a rod N upon which are adjustably mounted paper feed rolls O which are adapted to engage the top of the platen. This construction is or may be that of the usual paper holding bail of a Royal typewriting machine. There is also shown in the drawings a tabulator stop rod P.

Attached to the top plate at the rear of the machine by screws 2, are bracket members 1, each of which has a vertical portion 3 and a lower horizontal portion 4 terminating in an ear, through which passes an adjustable screw 5, the end of which engages the main frame of the machine. By a proper adjustment of these screws 5, the brackets may be positioned when the parts are assembled. A vertical member 6 is attached to each portion 3 of the bracket by rivets 7 and at its upper end has the horizontal portion 8 to which a track rail 9 is attached by a screw 10. The member 6 has a lower horizontal portion 11 to which a lower track rail is attached by a screw 13. The construction thus far described results in a track for the paper frame which is carried solely by the main frame of the typewriting machine and is simple in construction and readily attached to or detached from said frame.

The roll supporting frame includes a top member 14 having downwardly extending side portions 15 to which a bottom member 16 is attached by rivets 17. A brace 18 also connects the side members 15 intermediate their ends and is attached thereto by rivets 19. The member 14 is provided with a number of openings 20 for a purpose hereinafter set forth. The upper portion of the roll supporting frame comprises a side member 21 shown in Figure 5, corresponding side member 22, shown in Figures 6 and 7, both mem-

- bers being substantially right angular in form and the lower portion thereof being provided with openings 23 which are spaced similar to the openings 20 in the member 14.
- 5 The side members 21 and 22 can be adjustably positioned with regard to the member 14 and held in position by thread screws 24 passing through the openings 23 and threaded into tapped holes 20 in the member 14.
- 10 The brace 18 of the lower portion of the frame carries two or more double coned ball bearing rollers 25, each mounted to rotate freely on a pivot 26 which is carried by said brace. This pivot 26 may be threaded 70 at each end and provided with nuts whereby its position may be adjustable relative to the brace 18. The lower connecting cross-piece 16 also supports two ball bearing rollers 27 which are mounted to rotate on 75 pivots 28, passing through said brace 16 and held in position by nuts. Held in position by these same members 28 are clips 29, which extend forwardly and upwardly to partially surround the rail 12 and prevent any accidental displacement of the rollers 27 from 80 engagement with the track rail 12.

The upper ends of the side members 21 and 22 are provided with open end slots 30 adapted to receive spindles 31 for the paper roll. These spindles are provided near each end with a groove 32 outside of which is a knurled portion 33 for convenience in handling. It will be noted that the whole weight of the attachment and roll lies to 95 the rear of the supporting rollers 25. For this reason the lower rollers 27 are mounted horizontally and rest against the rear of the track rail 12, thus resisting the tendency of the whole frame to swing rearwardly. The 100 use of the double coned rollers 25 in connection with a round track rail enables the frame to adjust itself to any inequalities of position and to run freely without placing any strain upon the carriage of the typewriting machine.

Attached to the right hand member 15 by the same rivets 19 which hold the brace 18 in position, is an outwardly and forwardly extending arm 34 provided near its front end with an elongated opening 35. In this opening fits a pin 36 carried by a member 37 having an opening 38 which fits over the tabulating stop bar P at its end and is held in position by the adjusting nut of said rod. 105 The member 37 has a forwardly extending ear provided with an opening 39 through which passes a fastening member 40 into the side frame of the carriage. It will be observed that any relative fore and aft movement between the carriage and the paper roll supporting attachment which may be rendered necessary in assembling the parts or may be produced in operation, will be permitted by the elongated slot 35.

85 The roll carrying rod N is provided with

arms 41 to which is attached a right angular member having a horizontal cutting edge 42 providing a paper cutting knife. Any movement of this member in one direction is limited by the stops 43.

70 Paper fed from the roll will pass downwardly over the usual paper table K between the platen and the front and rear feed rolls up over the front of the platen and under the feed rolls O and knife 42. Whenever a form is completed or a sheet of desired length has been written, the papers will be fed forward until the bottom of the sheet registers with the edge of the paper knife, whereupon it can be readily torn off. 80

75 It will be noted that the roll holding attachment hereinbefore described places no extra weight upon the typewriting machine carriage and that due to the particular track upon which said frame travels, it imposes 85 but little additional work upon the endwise movement of the typewriting machine. Due to the elongated pin 36 the up and down shifting movement of the platen carriage may take place without in any way 90 effecting the operative relation between the carriage and the paper roll carrying attachment. The attachment may be removed in whole or in part readily or may be disconnected from the typewriting carriage. It is especially to be noted that the provision of this attachment in no way modifies any of the usual members of the typewriting machine, nor interferes in any way with the usual ordinary efficient operation. It is obvious that 95 various details may be modified and that parts of the invention may be used in other relations without in any way departing from the spirit of the invention. It is also to be understood that the attachment may 100 be used with typewriting machines, combined typewriting and computing machines, or any devices of similar character, in which a paper roll supporting frame is designed to have endwise movement simultaneously 105 with the carriage of a writing or similar machine. Wherever the term typewriting machine is employed in the claims, it is to be understood as having this broader significance. In general, it may be stated that 110 the invention is to be regarded as limited only by the scope of the appended claims.

115 I claim:

1. A roll carrying attachment for writing machines comprising brackets supported by 120 the machine frame and provided with upper and lower track rails; and a roll supporting frame having double coned rollers running on top of said upper rail, and rollers running on the rear side only of said lower rail; the center of gravity of the roll supporting frame being in the rear of a vertical plane passing through said track rails. 125

2. A roll carrying attachment for writing machines comprising brackets supported by 130

the machine frame and provided with upper and lower track rails; and a roll supporting frame having double coned rollers running on top of said upper rail, rollers running 5 on the rear side only of said lower rail, and means preventing accidental disengagement of the rollers and lower rail; the center of gravity of the roll supporting frame being in the rear of a vertical plane passing 10 through said track rails.

3. A roll carrying attachment for writing machines comprising brackets supported at their upper ends by the machine frame and having at their lower ends adjusting screws 15 which pass therethrough and bear against said machine frame, and upper and lower track rails supported by said brackets; and a roll supporting frame having double coned rollers running on top of said upper rail 20 and rollers running on the rear side of said lower rail; the center of gravity of said roll supporting frame being in the rear of a vertical plane passing through said track rails.

4. A roll carrying attachment for writing 25 machines comprising brackets supported by the machine frame and provided with upper and lower trap rails having curved contours; and a roll supporting frame having spaced 30 double coned rollers running on top of said upper rail and rollers running on the rear side of said lower rail; the center of gravity of the roll supporting frame being in the rear of a vertical plane passing through said trap rails.

35 5. A roll supporting attachment for writing machines comprising brackets supported by the machine frame and provided with track rails, a roll support proper running on said track rails and composed of a lower 40 portion and an upper portion adjustably mounted thereon, and loose connections between the carriage of the writing machine and the lower portion which compel move-

ment of the support and carriage together in one direction and permit relative movement in other directions. 45

6. A roll supporting attachment for typewriting machines having a carriage shiftable for case shift, comprising a supporting track carried entirely by the machine frame, 50 a roll support having a lower portion running on said track and an upper portion adjustably mounted on said lower portion, and loose connections between the carriage and the roll support which compel the carriage and support to travel in unison but permit independent shifting movements of the carriage. 55

7. A roll supporting attachment for typewriting machines having a carriage shiftable for case shift, comprising a supporting track adjustably carried by the machine frame, a roll support having a lower portion running on said track and an upper portion 60 adjustably mounted on said lower portion, 65 and loose connections between the carriage and the roll support which compel the carriage and support to travel in unison but permit independent shifting movements of the carriage and independent adjustment of the supporting track. 70

8. A roll supporting attachment for writing machines comprising a supporting track entirely carried by the machine frame; and a roll support comprising upper and lower 75 portions, the lower portion running on said track and having a horizontal portion provided with a plurality of spaced openings, and the upper portion composed of two side members having bases also provided with 80 openings, and means for fastening the side members adjustably to said horizontal portion.

In testimony whereof, I have hereunto subscribed my name.

LEWIS C. MYERS.
